(57) **CLAIM**

The ornamental design for a trolley, as shown and described.

DESCRIPTION

FIG. 1 is a perspective view of a trolley, showing the new design in an unfolded configuration;

FIG. 2 is a front elevational view thereof;

FIG. 3 is a rear elevational view thereof;

FIG. 4 is a left-side elevational view thereof, the right-side elevational view being a mirror image thereof;

FIG. 5 is a top plan view thereof; and

FIG. 6 is a bottom plan view thereof.

FIG. 7 is a perspective view thereof in a folded configuration;

FIG. 8 is a front elevational view of FIG. 7;

FIG. 9 is a rear elevational view of FIG. 7;

FIG. 10 is a left-side elevational view of FIG. 7, the right-side elevational view being a mirror image thereof;

FIG. 11 is a top plan view of FIG. 7; and,

FIG. 12 is a bottom plan view of FIG. 7.
